poration of California

Application July 28, 1945, Serial No. 607,526

11 Claims. (Cl. 103—46)

1

My invention relates to the well pumping art, and more particularly to a fluid-operated well pumping device adapted to alternatively pump oil from any one or more of a plurality of producing well strata in a well, as desired.

The invention is of particular utility in the oil industry in the production of oil wells and is particularly useful in combination with a fluid-operated well pump, and, consequently, it will be described in connection therewith, although it will be understood that the invention is susceptible of other uses and I do not intend to be limited to the specific embodiment disclosed and described herein.

Oil wells commonly include several independent strata from which oil may be produced. Usually when an oil well is drilled, it is intended to produce from a particular known stratum, although frequently there are other shallower producing strata in the well but of less desirable characteristics. For example, the shallower strata may be of low productivity, or the oil therefrom may be of inferior quality. Consequently, it is the usual practice to produce from the most desirable stratum until such time as it becomes uneconomical and then to close off such stratum and produce from an upper stratum of the well. Sometimes the oil from several strata is allowed to flow into and mix in the well, and the mixture is produced by pumping or otherwise. Such practices are often undesirable, and it is a primary object of my present invention to provide an apparatus by which several well strata may be separately but alternatively produced, preferably by pumping therefrom, so that the relative production from the several strata may be governed and controlled, as desired.

Another object of the invention is to provide an apparatus whereby the flow from several well strata may be mixed in desired proportions, so as to attain a mixture having predetermined characteristics, and then to pump the mixture to the surface of the well by suitable pumping means.

A further object of my invention is to provide a packer in a well between producing strata, separating the same into upper and lower production zones, providing valve means communicating with both zones, and providing a well tubing having an inlet adapted to cooperate with the valve means to connect selectively the inlet with either or both zones.

Still another object of the invention is to provide an apparatus for pumping from either or

2

both of two producing well strata, in which the flow from the strata or stratum, as the case may be, is freed of entrained gas before it is conveyed to the pump inlet. To accomplish this, I prefer to provide a fluid reservoir at atmospheric or casing head pressure into which the flow from the well strata is discharged to permit the separation therefrom of the entrained gas, the pump inlet being connected with the bottom of the reservoir so that the well fluid therefrom is conveyed to the pump under a substantial pressure created by the head of well fluid in the reservoir.

Another object of the invention is to provide a two-zone pumping apparatus as generally described above, in which the flow from the respective well zones is controlled by vertically moving the power tubing relative to the production tubing, the fluid-operated pump being moved with the power tubing.

20 A further object of the invention is to provide a two-zone pumping apparatus and a power tubing, in which one of the tubings is vertically movable relative to the other to control the proportion of flow from each of the production zones, there being mechanical apparatus provided for causing such vertical movement of the movable tubing. As it is desirable to effect such movement of the movable tubing during pumping operation and without cessation thereof, I 25 provide a novel form of casing head adapted to accomplish this, and this is a further object of the invention.

Other objects and advantages will be apparent from the following specification and the drawings, which are for the purpose of illustration only, and in which:

Fig. 1 is a diagrammatic assembly view, showing my invention installed in a well;

Fig. 2 is a vertical sectional view of the casing head of the invention;

Fig. 3 is a vertical sectional view of the device extending downwardly from the bottom of Fig. 2;

Fig. 4 is a vertical sectional view of the device extending downwardly from the bottom of Fig. 3;

45 Fig. 5 is a vertical sectional view extending downwardly from the bottom of Fig. 4;

Fig. 6 is a cross-sectional view taken on the line 6—6 of Fig. 2;

Fig. 7 is a cross-sectional view taken on the line 7—7 of Fig. 3;

Fig. 8 is a cross-sectional view taken on the line 8—8 of Fig. 4;

Fig. 9 is a cross-sectional view taken on the line 9—9 of Fig. 4;

55 Fig. 10 is a vertical sectional view of a por-

tion of the invention showing the valve mechanism thereof in one operating position:

Fig. 11 is a vertical sectional view similar to Fig. 10, but showing the valve mechanism in an alternative operating position; and

Fig. 12 is a vertical sectional view similar to Fig. 10, but showing the valve mechanism in another alternative operating position.

Referring to the drawings, Fig. 1 shows an oil well 15 having a casing 16 set therein in the customary manner, the casing having perforations 17 therein disposed to register with an upper producing well stratum A, and having perforations 18 therein adapted to register with a lower producing well stratum B. The upper end of the casing 16 is provided with a casing head 19 from which a production tubing 20 extends downwardly into the well. Connected to the lower end of the production tubing 20, and extending downwardly therefrom in the well 15, is mechanism to be described hereinafter, which includes an upper well packer 21, preferably of the swab type, and a lower well packer 22, preferably of the hook-wall type well known in the art. The upper well packer 21 forms a fluid-tight seal with the inner wall of the casing 16 so as to provide therein a reservoir well zone 23. Similarly, the lower well packer 22 forms a fluid-tight seal with the inner wall of the casing 16 and divides the casing below the upper well packer 21 into an upper well zone 24 communicating through the perforations 17 with the upper producing well stratum A, and a lower well zone 25 communicating through the perforations 18 with the lower producing well stratum B.

Referring to Fig. 2 of the drawings, the casing head 19 includes a bottom plate 27 provided with a tubular portion 28 in which the upper end of the casing 16 is threaded, the bottom plate being suitably secured as by bolts 29 to a lower body member 30 of the casing head. The lower face of the lower body member 30 has depending therefrom a tubular portion 31 to which is secured, as by means of a collar 32, the upper end of the producing tubing 20. The upper end of the lower body member 30 is provided with a central bore 33 which receives a tubular sleeve 35 passing therethrough, the lower portion of the central bore 33 being provided with a counterbore 36 so as to form an annular fluid passage 37 between the tubular sleeve 35 and the counterbore 36. The upper portion of the lower body member 30 is provided with a radial discharge port 38 which communicates with the annular fluid passage 37 and with a discharge tubing 39 leading to a suitable point of disposal or use (not shown).

Secured to the upper end of the lower body member 30, as by bolts 41, is an upper body member 42 of the casing head 19, the upper body member being provided with a central bore 43 axially aligned with the central bore 33, through which extends the upper end 44 of a power tubing 45, the central bore 43 being provided with a counterbore 46 forming an annular fluid passage 47 between the counterbore and the power tubing 45. The upper body member 42 is provided with a radial inlet port 48 communicating between the annular fluid passage 47 and a supply tubing 49, the supply tubing leading to a suitable source of fluid under high pressure (not shown). The upper end of the tubular sleeve 35 is received in a counterbore 50 of the upper body member 42, the inner diameter of the sleeve 35 being approximately equal to the diameter of

the counterbore 46 so that the annular fluid passage 47 extends downwardly between the power tubing 45 and the inner wall of the sleeve. A packing gland 51 is provided in the upper end of the upper body member 42 to provide a fluid-tight seal between the body member and the power tubing 45 passing therethrough.

Secured to the upper end of the upper body member 42, as by a set-screw 53, is a tubular member 54 having an annular supporting ring 55 welded or otherwise secured to the inner wall thereof and which supports a ball bearing 56 which in turn supports a rotatable gear wheel 57 having gear teeth 58 on the periphery thereof adapted to be engaged by a pinion 59 provided on a rotatable shaft 60. The gear wheel 57 is provided with a threaded opening 61 therethrough which receives square threads 62 formed on the power tubing 45. As will be appreciated, rotation of the shaft 60 and the pinion 59 causes rotation of the gear wheel 57, to raise or lower the power tubing 45, depending upon the direction of rotation of the gear wheel. Threaded on the upper end of the power tubing 45 is a closure plug 63 having an end plug 64 threaded thereto and adapted for engagement by conventional well rig tools for pulling the tubing, as is well known in the art. As will also be noted, the lowermost portion of the power tubing 45 seen in Fig. 2 is provided with a plurality of radial ports 65 which provide fluid communication between the annular fluid passage 47 and the interior of the power tubing 45.

Referring to the upper portion of Fig. 3, the lower end of the tubular sleeve 35 is threaded to an annular plug 67 which retains a chevron packing 68 adapted to form a fluid-tight seal between the tubular sleeve and the outer wall of the power tubing 45. Connected to the lower end of the power tubing 45, and adapted to be supplied with operating fluid under high pressure therefrom, is a fluid-operated pump unit 69, comprising the pumping means of the invention, which has discharge ports 70 which communicate with the interior of the production tubing 20, the fluid-operated pump unit being of any type well known in the art. The lower end of the fluid-operated pump unit 69 has threaded therein an annular inlet member 71 which is adapted to be supported by a tubular sleeve 72 which is threaded into the lower end of the production tubing 20. Threaded into the pump inlet member 71 and extending downwardly therefrom is a tubular valve member 73 which makes a close sliding fit with the bore 74 of the sleeve 72. Thus, engagement of the pump inlet member 71 with the upper end of the sleeve 72 limits downward movement of the fluid-operated pump 69 relative to the production tubing 20, but permits upward movement therebetween.

Threaded to the lower end of the tubular sleeve 72 is an upper tubular valve body 76 having radial ports 77 which communicate with registering ports 78 of a sleeve 79 carried on the outer wall of the upper valve body 76. The sleeve 79 is retained in place on the upper valve body 76 by an upper collar 80 threaded to the upper valve body and a lower collar 81 (shown in Fig. 4) welded or otherwise secured thereto. The lower portion of the sleeve 79 is reduced in diameter to cooperate with a bore 83 of a tubular packer element 84 to define an annular passage 85 therebetween. The lower portion of the tubular member 73 has a portion 86 of reduced diameter, 75 forming an annular fluid passage 87 adapted to

communicate between the radial ports 11 of the upper tubular valve body 76 and radial ports 88 formed in the tubular member. As will also be noted, the upper end of the annular fluid passage 85 communicates with circumferentially spaced longitudinal ports 89, the upper ends of which communicate with the interior of an upwardly extending tube 90, the upper end of which is open to the casing 16. Carried on the tubular packer element 84 is the upper well packer 21 which is held in longitudinal position thereon by a sleeve 92, the lower end of which, as seen in Fig. 4, abuts against a collar 93 threaded to the lower end of the tubular packer element 84.

Referring to Fig. 4, the lower end of the upper tubular valve body 76 is provided with an enlarged head 94 which abuts against the upper end of an intermediate valve body 95, the lower end of which abuts against the upper end of a lower valve body 96, the upper valve body 76, the intermediate valve body 95, and the lower valve body 96 being rigidly secured in axial alignment by a longitudinal tie bolt 97. The head 94 is provided with a longitudinally drilled passage 98 which is axially aligned with a longitudinal bore 99 formed in the intermediate valve body 95 and with a longitudinally drilled passage 100 in the lower valve body 96. Disposed in the bore 99 is a compression spring 102, the upper end of which engages an upper spring follower 103 and the lower end of which engages a lower spring follower 104, the upper spring follower supporting an annular valve cup 105 which in turn supports an upper ball valve member 106, and the lower spring follower 104 engages an annular valve cup 107 which in turn engages a lower ball valve member 108. As will be understood, the spring 102 normally retains the upper ball valve member 106 in engagement with the drilled passage 98 to close the same, and maintains the lower ball valve member 108 in engagement with the passage 100 to close it. The lower end of the head 94 is counterbored to provide an upper chamber 110 in which the upper ball valve member 106 is disposed, and the upper end of the lower valve body 96 is counterbored to provide a lower chamber 111 in which the lower ball valve member 108 is disposed. The lower valve body 96 is also provided with a depending tubular extension 112, the lower end of which is threaded into a foot member 113.

Clamped between the lower valve body 96 and the foot member 113 is a tubular sleeve 114 which defines an annular passage 115 communicating between the longitudinally drilled passage 100 of the lower valve body 96 and a plurality of circumferentially spaced longitudinal passages 116 provided in the foot member. Also carried by the foot member 113 is an upwardly extending tubular sleeve 118, the upper end of which makes a sliding fit into the lower end of the tubular packer element 84 and is provided with perforations 119. The tubular sleeve 118 cooperates with the sleeve 114 to form an annular fluid passage 120 therebetween which communicates at its upper end with the longitudinally drilled passage 98 of the head 94, and which communicates at its lower end with a plurality of circumferentially spaced longitudinal passages 121 formed in the foot member 113.

Also carried by the foot member 113 is an outer tubular sleeve 122, the upper end of which is secured, as by welding or otherwise, to the collar 93, which with the sleeve 118 forms an annular passage 123 therebetween communicating at its

upper end with the perforations 119 and communicating at its lower end with circumferentially spaced radial ports 124, the inner ends of which communicate with a bore 125 formed in the foot member 113.

The lower end of the tubular member 73 is closed by a plug 127 threadedly secured thereto, the plug also having threaded thereto and depending therefrom a tubular valve element 128 which makes a close sliding fluid-tight fit in the central bores of the upper tubular valve body 76, the intermediate valve body 95, and the lower valve body 96, the lower end of the valve element being open so as to communicate with the radial ports 124 of the foot member 113. The central portion of the valve element 128 is reduced in diameter to provide an annular channel 129, the upper end of which communicates with an upper helical groove 130, and the lower end of which communicates with a lower helical groove 131, and radial ports 132 are provided to communicate between the channel 129 and the interior of the valve element. The upper helical groove 130 is reduced in cross-sectional area as it extends upwardly, and the lower helical groove 131 is reduced in cross-sectional area as it extends downwardly, for a purpose to be described hereinafter.

Connected to and depending from the foot member 113 is a tubing section 133 having perforations 134 therein which provide communication between the interior of the tubing section and the upper well zone 24. Also threaded to the lower portion of the foot member 113 is an inlet tubing 135 which, together with the tubing section 133, defines an annular fluid passage 136 therebetween which communicates at its upper end with the longitudinal passages 121 of the foot member. The interior of the inlet tubing 135 communicates at its upper end with the longitudinal passages 116 of the foot member.

As seen in Fig. 5, the lower end of the tubing section 133 is threaded into the upper end of the lower well packer 22 which engages the inner wall of the casing 16 to form a fluid-tight seal therewith, the packer being provided at its lower end with a depending bull plug 137 having perforations 138 therein which provide communication between the interior of the bull plug and the lower well zone 25. The lower portion of the inlet tubing 135 extends downwardly through the lower well packer 22 and into the bull plug 137 to a point adjacent the lower end of the bull plug, as best seen in Fig. 1, the bull plug and inlet tubing forming a gas anchor, as will be understood by those skilled in the art.

With the bottom hole parts of the device assembled as illustrated in Figs. 3, 4, and 5, it will be noted that the inlet member 71 of the fluid-operated pump unit 69 engages and is supported on the top of the tubular sleeve 72, in which position the valve element 128, as seen in Fig. 4, is so disposed relative to the valve bodies 76, 95, and 96 that the annular channel 129 on the valve element 128 is out of communication with the chambers 110 and 111, and consequently no fluid may flow from either of the drilled passages 98 or 100 to the interior of the valve element. Normally, it is preferable to install the unit in a well with the parts in the position just described.

In operation, if it is desired to pump at full capacity from the lower well zone 25, the power tubing 45 is vertically positioned relative to the production tubing 20 so that the valve element 128 is disposed relative to the valve bodies 76, 95,

and 96 as illustrated in Fig. 10, in which the annular channel 129 registers directly with the lower chamber 111. Operating fluid, such as oil under high pressure, is delivered through the power tubing 45 to the fluid-operated pump unit 69 so as to actuate the same as is well known in the art. Well fluid then flows from the lower producing zone B through the perforations 18 in the casing 16 into the lower well zone 25, and flows therefrom through the bull plug 137 and the inlet tubing 135, comprising a gas anchor of the invention, into the inlet tubing. Such well fluid from the lower well zone 25 flows from the inlet tubing 135 upwardly through the longitudinal passages 116 of the foot member 113 into the annular passage 115 and upwardly therethrough and into the longitudinally drilled passage 100 in the lower valve body 96. The well fluid then raises the lower ball valve member 108 and flows through the lower chamber 111 into the annular channel 129. From the annular channel 129 the well fluid flows through the radial ports 132 into the tubular valve element 128 and downwardly therethrough into the depending tubular extension 112. From the tubular extension 112 well fluid flows outwardly through the radial ports 124 in the foot member 113 into the annular fluid passage 123 and upwardly therethrough. From the upper end of the annular fluid passage 123 the well fluid flows inwardly through the perforations 119 of the tubular sleeve 118 into the annular fluid passage 85, through which it flows upwardly to discharge through the longitudinal ports 89 into the lower end of the upwardly extending tube 90, through which it in turn flows upwardly to discharge into the reservoir well zone 23. Since the upper end of the upwardly extending tube 90 is at all times above the liquid level in the reservoir well zone 23, any gas mixed with the well fluid can separate therefrom and pass upwardly through the casing 16 between the casing and the production tubing 20.

Well fluid flows from the lower portion of the reservoir well zone 23 inwardly through the radial ports 82 formed in the tubular packer element 84 and through the ports 78 and 77 to the annular fluid passage 87 through which it flows downwardly to enter the tubular member 73 through the radial ports 88. The well fluid then flows upwardly through the tubular member 73 to enter the fluid-operated pump unit 69 through the annular inlet member 71. As will be noted, the inlet member 71 of the fluid-operated pump unit 69 is disposed at all times below the upper liquid level of well fluid in the reservoir well zone 23, so that the fluid in such zone entering the fluid-operated pump unit is at all times under some pressure so as to maintain any gas therein in solution, to provide maximum volumetric efficiency of the fluid-operated pump unit 69, which is another feature of the invention.

Well fluid is discharged from the fluid-operated pump unit 69 through the discharge ports 70 thereof into the production tubing 20, being pumped upwardly therethrough to pass through the annular fluid passage 37 of the casing head 19 and discharging through the radial discharge port 38 into the discharge tubing 39 to be conveyed to a suitable point of use or disposal (not shown).

The position of the tubular valve member 128 shown in Fig. 10 may be referred to as a first operating position, in which the full flow from the lower well zone 25 is produced by the fluid-operated pump unit 69. In this position, it will be

noted, the upper helical groove 130 does not register with the upper chamber 110, and consequently, as will be seen hereinafter, no well fluid is produced in this position from the upper well zone 24. It will also be understood that in the event that less than full flow of the production from the lower well zone 25 is desired, the tubular valve element 128 may be lowered so as to cause the upper helical groove 130 to register with the lower chamber 111, in which case the flow from the lower well zone is throttled by the restricted cross-sectional area of the upper helical groove. As will be obvious, since the cross-sectional area of the upper helical groove 130 is reduced as it extends upwardly, any desired variation in the flow from the lower well zone may be obtained by suitable positioning of the valve element 128.

Adjustment of the tubular valve element 128, by vertical movement thereof, is accomplished by raising or lowering the power tubing 45, which is accomplished by actuation of the special casing head 19, as best shown in Fig. 2. Since the upper end 44 of the power tubing 45 is threaded secured to the gear wheel 51, rotation of the gear wheel, by rotation of the shaft 60 and the pinion 59, provides the desired vertical adjustment of the power tubing 45. When the power tubing 45 is raised so as to move the fluid-operated pump unit 69 out of engagement with the tubular sleeve 72, upon which it rests as shown in Fig. 3, the full weight of the power tubing and pump will be supported by the gear wheel 57, which in turn is rotatably supported by the thrust bearing 56. Thus, the casing head 19 provides mechanical means for vertically adjusting the position of the power tubing 45 relative to the production tubing 20 whereby production from the well is controlled as desired.

Operating fluid, such as oil under high pressure, is conveyed to the fluid-operated pump unit 69 through the power tubing 45 to operate the pump unit, as is well known in the art. Such operating fluid passes through the casing head 19, being introduced thereto from the supply tubing 49 and passing through the radial inlet port 48, the annular fluid passage 47, and the radial ports 65 into the power tubing 45, through which it flows downwardly to the fluid-operated pump unit 69.

With the parts in the position illustrated in Fig. 11, which may be termed a second operating position, the annular channel 129 of the tubular valve element 128 registers with both the upper chamber 110 and the lower chamber 111 so as to permit well fluid from both the upper well zone 24 and the lower well zone 25 to flow to the fluid-operated pump unit 69. Flow from the lower well zone 25 is as described above in connection with Fig. 10. Fluid from the upper well producing stratum A flows through the perforations 17 of the casing 16 into the upper well zone 24, passing inwardly through the perforations 134 into the tubing section 133. Such well fluid from the upper well zone passes through the annular fluid channel 136 and upwardly therethrough and through the longitudinal passages 121 of the foot member 113 to the annular fluid passage 120, through which it flows upwardly to enter the longitudinally drilled passage 98 of the head 94. Such well fluid displaces the ball valve member 108 from its seated position as illustrated in Fig. 4, to flow into the upper chamber 110 and thence through the annular channel 129 and the radial ports 132 to the interior of the tubular valve element 128, commingling with the well fluid from

the lower well zone 25. Thus, in this second operating position, the annular inlet member 71 of the fluid-operated pump unit 69 is in open communication with both the upper and lower well zones 24 and 25, and well fluid is pumped from both zones.

In the position illustrated in Fig. 12, which may be termed a third operating position, the tubular valve element 128 is adjusted vertically to a position in which the annular channel 129 thereof communicates only with the upper chamber 110, the lower helical groove 131 being out of communication with the lower chamber 111. In this third operating position well fluid from the upper well zone 24 may flow directly to the fluid-operated pump unit 69, as described above, but the lower well zone 25 is closed off from communication therewith. Thus, in this position only the upper well zone 24 will be produced. Obviously, the tubular valve element 128 may be positioned intermediate the positions illustrated in Figs. 11 and 12, in which the annular channel 129 communicates with the upper chamber 110 and the lower helical groove 131 communicates with the lower chamber 111, in which intermediate position the full flow from the upper well zone 24 will be produced, but only a restricted flow from the lower well zone 25 will be admitted through the lower helical groove.

Other intermediate operating positions in which the tubular valve element 128 may be positioned will be apparent to those skilled in the art, and it will be understood that the invention provides means whereby the upper and lower well zones 24 and 25, respectively, may be produced simultaneously or alternatively as desired. Control of such production, obviously, is obtained through vertical movement of the power tubing 45, as described above.

Although I have shown and described a preferred embodiment of my invention, it will be understood that certain parts and elements thereof are merely representative of other parts and elements which may be substituted therfor without departing from the spirit of the invention, and consequently I do not intend to be limited to the embodiment shown, but desire to be afforded the full scope of the following claims.

I claim as my invention:

1. In a fluid-operated well pumping device, the combination of: packer means adapted to be set in a well between an upper and a lower producing well stratum so as to separate the well into an upper well zone communicating with said upper stratum and a lower well zone communicating with said lower stratum; fluid-operated pumping means associated with said packer means and having a pump inlet, said pumping means being adapted to pump well liquid upwardly through said well; power tubing extending downwardly in said well and connected to said pumping means and adapted to supply operating fluid thereto; and means for opening communication between said pump inlet and either of said zones selectively, including means for moving said power tubing vertically in the well so as to move said pumping means relative to said packer means.

2. In a well pumping device, the combination of: packer means adapted to be set in a well between an upper and a lower producing well stratum so as to separate the well into an upper well zone communicating with said upper stratum and a lower well zone communicating with said lower stratum; a production tubing extending down-

wardly in said well; pumping means in said production tubing and having a pump inlet, said pumping means being adapted to pump well liquid upwardly through said production tubing; power tubing extending down into said well and connected to said pumping means to supply operating fluid thereto; and means for opening communication between said pump inlet and either of said zones selectively, including means for moving mechanically one of said tubings relative to said packer means.

3. In a fluid-operated well pumping device, the combination of: packer means adapted to be set in a well between an upper and a lower producing well stratum so as to separate the well into an upper well zone communicating with said upper stratum and a lower well zone communicating with said lower stratum; pumping means associated with said packer means and having a pump inlet, said pumping means being adapted to pump well liquid upwardly through said well; power tubing extending downwardly in said well and connected to said pumping means to supply operating fluid thereto; and means for opening communication between said pump inlet and either of said zones selectively, including means for moving mechanically said power tubing vertically in the well so as to move said pumping means relative to said packer means.

4. In a well device, the combination of: first packer means adapted to be set in a well between an upper and a lower producing well stratum so as to separate the well into an upper well zone communicating with said upper stratum and a lower well zone communicating with said lower stratum; second packer means adapted to be set in the well to form a reservoir zone thereabove separated from said upper and lower zones by said second packer means; and means for selectively opening communication between said reservoir zone and said upper well zone and said lower well zone.

5. In a well pumping device, the combination of: first packer means adapted to be set in a well between an upper and a lower producing well stratum so as to separate the well into an upper well zone communicating with said upper stratum and a lower well zone communicating with said lower stratum; second packer means adapted to be set in the well to form a reservoir zone thereabove separated from said upper and lower zones by said second packer means; means for selectively opening communication between said reservoir zone and said upper well zone and said lower well zone; and pumping means having a pump inlet communicating with said reservoir zone, said pumping means being adapted to pump well fluid from said reservoir zone upwardly through the well.

6. In a well pumping device, the combination of: first packer means adapted to be set in a well between an upper and a lower producing well stratum so as to separate the well into an upper well zone communicating with said upper stratum and a lower well zone communicating with said lower stratum; second packer means adapted to be set in the well to form a reservoir zone thereabove separated from said upper and lower zones by said second packer means; means for selectively opening communication between said reservoir zone and said upper well zone and said lower well zone; and pumping means having a pump inlet communicating with said reservoir zone, said pumping means being adapted to pump well fluid from said reservoir zone upwardly through

11

the well, said pump inlet communicating with said reservoir zone at a point below the point of communication of said upper and lower well zones with said reservoir zone so as to allow gas to separate from the well fluid in said reservoir zone before the well fluid is conveyed into said pumping means.

7. In a well pumping device, the combination of: production tubing adapted to be disposed in a well and adapted to receive therein a well pump; tubular means connected to the lower end of said production tubing and extending downwardly therefrom; first packer means on said tubular means and adapted to form a fluid seal between said tubular means and the wall of the well to define a first zone above said first packer means; second packer means on said tubular means below said first packer means and adapted to form a second fluid seal between said tubular means and the wall of the well to define a second zone between said first and second packer means and to define a third zone below said second packer means; and passage means in said tubular means connecting said second and first zones and connecting said first and third zones.

8. In a well pumping device, the combination of: production tubing adapted to be disposed in a well and adapted to receive therein a well pump; tubular means connected to the lower end of said production tubing and extending downwardly therefrom; first packer means on said tubular means and adapted to form a fluid seal between said tubular means and the wall of the well to define a first zone above said first packer means; second packer means on said tubular means below said first packer means and adapted to form a second fluid seal between said tubular means and the wall of the well to define a second zone between said first and second packer means and to define a third zone below said second packer means; passage means in said tubular means connecting said second and first zones and connecting said first and third zones; and valve means in said tubular means and adapted to control the flow of fluid through said passage means.

9. In a well pumping device, the combination of: a production tubing adapted to be extended downwardly into a well; a fluid-operated well pump in said production tubing; a power tubing extending downwardly into said production tubing and having its lower end connected to said pump to supply operating fluid thereto; and a

12

5 casing head connected to the upper ends of said tubings, said casing head having a discharge port communicating with the interior of said production tubing and having an inlet port communicating with the interior of said power tubing, and having means for moving said power tubing vertically relative to said production tubing so as to dispose said pump at different levels therein.

10. In a well pumping device, the combination of: a production tubing adapted to be extended downwardly into a well; a power tubing adapted to be extended downwardly into the well; and a casing head having the upper end of said production tubing rigidly connected thereto and having the upper end of said power tubing extending thereto, said casing head being provided with rotatable means engaging the upper end of said power tubing and adapted when rotated to raise said power tubing relative to said production tubing.

20 11. In a well pumping device, the combination of: a production tubing adapted to be extended downwardly into a well; a power tubing adapted to be extended downwardly into the well; a stationary casing head connected to the upper ends 25 of said tubings, means on said head defining a discharge port communicating with the interior of said production tubing, means on said head defining an inlet port communicating with the interior of an elongated chamber surrounding 30 said power tubing, an opening in the wall of said power tubing within said chamber and in communication therewith, and means for moving said power tubing vertically in said chamber relative 35 to said chamber, production tubing and head without breaking said communication between said chamber and said power tubing.

CLARENCE J. COBERLY.
